METHOD AND APPARATUS FOR DRY
SPINNING FILAMENTSHugh Miller and William H. Kreamer, Meadville,
Pa., assignors to American Viscose Corporation,
Wilmington, Del., a corporation of Delaware

Application June 4, 1946, Serial No. 674,268

21. Claims. (Cl. 18—8)

1.

This invention relates to the supply of a fluid medium, such as air or other gas or vapor of controlled temperature to spinning machines comprising a plurality of spinning cells arranged in one or more rows.

The object of the present invention is to provide improved methods and apparatus for distributing a fluid medium, especially of gaseous nature, such as the evaporative medium to a plurality of dry-spinning cells, or the cooling medium to a plurality of melt-spinning cells, so that the amount and temperature conditions of the medium supplied to each spinning cell differs as little as possible from that supplied to the other cells. Other objects and advantages of the invention will be apparent from the drawing and the description thereof hereinafter.

In the drawing which is illustrative of preferred systems for executing the invention—

Figure 1 is a horizontal section taken on the line I—I of Figure 2;

Figure 2 is a vertical section taken on the line II—II of Figure 1;

Figure 3 is a horizontal section similar to that of Figure 1 of a modification;

Figure 4 is a horizontal section similar to that of Figure 1 of another modification;

Figure 5 is a horizontal section similar to that of Figure 1 of still another modification;

Figure 6 is a horizontal section through another modification; and

Figure 7 is a vertical section taken on line VII—VII of Figure 6.

In Figures 1 and 2, the system of the present invention is arranged to supply a fluid medium of gaseous or vaporous nature to one or two rows of spinning cells located laterally of a manifold duct. This embodiment is illustratively shown for supplying heated or cooled air to the spinning cells and comprises a feeding duct 2 connected to the discharge outlet of a blower or fan 3. The duct 2 has a plurality of ports 4 connected with side ducts or branch outlets 4 which communicate with the spinning cells 5. A return duct 6 surrounds the main supply duct 2 and receives excess fluid medium discharged from the open end 7 of duct 2. The wall of duct 2 constitutes a closed, heat-conductive partition preventing intermingling between the contents of the main supply duct 2 and the return duct 6, except at the open end 7 of duct 2. The return duct is well insulated against loss or gain of heat, as by the material 8. Fan 3 and the ducts connected thereto may also be insulated. Likewise, the spinning cells and any portion of the branch

outlets 4 which would otherwise be unprotected by the insulation 8 of the return duct 6 may be insulated in customary fashion. The spinning cells 5 may be surrounded by a jacket 8a which may be supplied with a heating medium or means in the case of dry spinning or with a cooling medium or means in the case of melt-spinning, though this is not essential. The return duct is connected by the discharge or exhaust conduit 9 to the inlet of the blower 3. The conduit 9 is also provided with any suitable heating or cooling means 10 which may take the form of a steam coil, an electric heater or the like, or a coil for a cooling brine or the like. An open branch conduit 11 provided with a filter 12 and an adjustable damper 13 may be provided to control the admission of supplemental air from the spinning room atmosphere or of some other supplemental gas or vapor, when used, from a suitable supply vessel thereof.

In practice, an excess of heated or cooled air or other gas or vapor medium is supplied to the duct 2 so that after the amount required by the spinning cells is withdrawn through the branches 4, a volume of the medium at least equivalent to the total amount supplied to the associated cells is re-circulated. The re-circulation of the excess fluid medium through the return duct which surrounds the main duct 2 and largely also the branch conduits 4 tends to maintain the temperature of the air supplied to the cells along the duct at uniform temperature conditions in spite of the temperature of the atmosphere in the spinning room. The damper 13 is adjusted so that anywhere from two to ten times the amount of air actually used by the spinning cells is introduced into the main duct 2.

In Figure 3 there is shown a modification in which the various elements corresponding to the elements of Figure 1 are designated by the same reference characters but with a postscript letter *a*. In this embodiment, the branch conduits 4a do not communicate directly with the conduit 2a but have open ends 4a' communicating with the surrounding duct 6a. Preferably, such openings 4a' are disposed closer to the outside surface of duct 2a than to the inside surface of duct 6a.

In Figure 4, elements corresponding to those in Figure 1 are designated by corresponding reference characters but with a postscript letter *b*. In this embodiment, the blower 3b discharges into the outer duct 6b and the branch conduits 4b derive their medium from communicating ports 4b' in the duct 2b.

In Figure 5, elements corresponding to those in Figure 4 carry the same reference characters except that the postscript is changed to letter *c*. In this embodiment, the branch conduits *4c* have their openings *4c* communicating with the outer duct *6c* and as in the embodiment of Figure 3, it is preferable that such communication be nearer the inside duct *2c* than the outside duct *6c*. As in Figure 4, the fluid is supplied to the outer duct and returns through the inner duct.

In the embodiment of Figures 6 and 7, a modified arrangement is shown in which a more refined control of the uniformity of temperature and rate of supply of evaporative or cooling medium to the several cells in a row is provided. As shown, a blower *15* discharges air through two supply ducts *16* and *17* which serve the opposite ends of two adjacent manifolds *18* and *19* respectively. The spinning cells *20*, which optionally may be insulated and/or provided with a heating or cooling jacket, as in the embodiment of Figures 1 and 2, are each connected to both manifolds by means of branch conduits *21* and *22*. As in the embodiment of Figures 1 and 2, excess air is supplied to the manifolds *18* and *19* and discharges from the open ends *23* and *24* thereof respectively into return ducts *25* and *26* surrounding the respective manifolds. These return ducts discharge into opposite side entrances *27* and *28* of the blower *15*. In this embodiment, any reduction in volume or change in temperature (whether decrease or increase) of the evaporative medium supplied through conduit *21* to the cell at the far end of duct *18* is compensated for by a corresponding greater supply through the conduit *22* at the near end of duct *19*. Such compensation is effected for the entire row of cells as is readily apparent from a study of the drawing.

While all of the embodiments shown are concerned with the supply of the evaporative or cooling medium to a single machine comprising one or two rows of cells, it is obvious that a single heating (or cooling) and blowing system may be arranged to supply a plurality of such machines. Again, separate heating (or cooling) and blowing systems may be associated with a spinning machine comprising a plurality of rows of spinning cells. Thus, instead of the single blower of Figures 6 and 7, a separate blower and heating (or cooling) system may be provided at opposite ends of the ducts *18* and *19* as in Figures 1 and 2. A spinning machine comprising a large number of rows of spinning cells may be provided with a plurality of evaporative or cooling medium supply ducts disposed between adjacent rows and fed alternately from blowers positioned at opposite ends thereof. The cells in the intervening rows may be connected to both manifolds disposed on adjacent sides of the rows, so as to compensate for reduction or rise in temperature or reduction of volumetric supply rate in the cells at the far end of each duct.

Changes and variations may be made without departing from the spirit and scope of the invention as defined in the appended claims.

We claim:

1. A spinning machine comprising a row of spinning cells, a duct for supplying a fluid medium to the cells, a return duct contiguous with the first duct, one of said ducts surrounding the other, conduits connecting the cells to one of the ducts at spaced points therealong, and extending through the other duct in heat exchanging relationship with the medium therein, means

for introducing the medium into one end of the supply duct, and the supply duct being constructed to discharge into the return duct adjacent the other end of the supply duct only.

5. 2. A spinning machine comprising a row of spinning cells, a duct for supplying a fluid medium to the cells, a return duct contiguous with the first duct, one of said ducts surrounding the other, conduits connecting the cells to the supply duct at spaced points therealong and extending through the return duct in heat exchanging relationship with the medium therein, means for introducing the medium into one end of the supply duct, and the supply duct being constructed to discharge into the return duct adjacent the other end of the supply duct only.

10 3. A spinning machine comprising a row of spinning cells, a duct for supplying a fluid medium to the cells, a return duct contiguous with the first duct, one of said ducts surrounding the other, conduits connecting the cells to the return duct at spaced points therealong and extending through the other duct in heat exchanging relationship with the medium therein, means for introducing the medium into one end of the supply duct, and the supply duct being constructed to discharge into the return duct adjacent the other end of the supply duct only.

15 4. A system for distributing a gaseous medium to a plurality of spaced units comprising a duct for supplying a fluid medium to the units, a return duct contiguous with the first duct, one of said ducts surrounding the other, conduits connecting the units to the supply duct at spaced points therealong and extending through the return duct in heat exchanging relationship with the medium therein, means for introducing the medium into one end of the supply duct, a communicating opening adjacent the other end of the supply duct between the supply duct and the return duct so that the supply duct discharges directly into the return duct, and an exhaust conduit connected to the return duct at a position remote from the communicating opening.

20 5. A system for distributing a gaseous medium to a plurality of spaced units comprising a duct for supplying a fluid medium to the units, branch conduits connecting the units to the duct at spaced points therealong, a return duct surrounding the supply duct, said branch conduits extending radially through the return duct in heat exchanging relationship with the medium therein, means for introducing the medium into one end of the supply duct, a communicating opening adjacent the other end of the supply duct between the supply duct and the return duct so that the supply duct discharges directly into the return duct, and an exhaust conduit connected to the return duct at a position remote from the communicating opening.

25 6. A system for distributing a gaseous medium to a plurality of spaced units comprising a duct for supplying a fluid medium to the units, branch conduits connecting the units to the duct at spaced points therealong, a return duct surrounding the supply duct, said branch conduits extending radially through the return duct in heat exchanging relationship with the medium therein, means for introducing the medium into one end of the supply duct, the supply duct being made of material having high heat-conductivity, a communicating opening adjacent the other end of the supply duct between the supply duct and the return duct so that the supply duct dis-

charges directly into the return duct, and exhaust conduit connected to the return duct at a position remote from the communicating opening.

7. A system for distributing a gaseous medium to a plurality of spaced units comprising the duct for supplying the fluid medium to the units, branch conduits connecting the units to the duct at spaced points therealong, a return duct surrounding the supply duct, said branch conduits extending radially through the return duct in heat exchanging relationship with the medium therein, means for introducing the medium into one end of the supply duct, a communicating opening adjacent the other end of the supply duct between the supply duct and the return duct, an exhaust conduit connected to the return duct at a position remote from the communicating opening, means connected between the conduit and the supply duct for recycling the medium, means associated with the recycling means for controlling the temperature of the medium, and means for controlling the introduction of additional medium into the recycling means in advance of a temperature-changing means.

8. A method of supplying fluid medium to a plurality of spinning cells comprising passing a stream of the fluid to a main supply duct in large excess of the amount required by the cells, then passing the stream directly from the supply duct into and through a contiguous return duct, withdrawing the fluid requirements for the cells from one duct at spaced points therealong and leading the fluid thus withdrawn through paths extending through the region enclosed by the other duct in heat exchanging relationship with the medium in the region, and maintaining the stream in the return duct in heat exchanging relationship with the stream in the main supply duct through a common closed heat conductive portion of the supply duct and the return duct therebetween along all of that portion of their length comprising said spaced points of withdrawal.

9. A spinning machine comprising a row of spinning cells, a duct for supplying a fluid medium to the cells, a return duct surrounding the supply duct, branch conduits connecting the cells and the supply duct, said conduits extending through the return duct in heat exchanging relationship with the region enclosed by the return duct, means for introducing the medium into one end of the supply duct, the supply duct being constructed to discharge into the return duct adjacent the other end of the supply duct.

10. A spinning machine comprising a row of spinning cells, a duct for supplying a fluid medium to the cells, a return duct surrounding the supply duct, branch conduits connecting the cells and the supply duct, said conduits extending through the return duct in heat exchanging relationship with the region enclosed by the return duct, means for introducing the medium into one end of the supply duct, the supply duct being made of material having high heat conductivity and being constructed to discharge into the return duct adjacent the other end of the supply duct, and means for insulating the outside of the return duct.

11. A spinning machine comprising a row of spinning cells, a duct for supplying a fluid medium to the cells, a return duct surrounding the supply duct, branch conduits connecting the cells and the supply duct, said conduits extending through the return duct in heat exchanging re-

lationship with the region enclosed by the return duct, means for introducing the medium into one end of the supply duct, the supply duct being made of material having high heat conductivity

5 and being constructed to discharge into the return duct adjacent the other end of the supply duct, means for changing the temperature of the medium therein by the return duct, and means for controlling the introduction of additional medium into the return duct in advance of the temperature changing means.

12. A method for supplying a fluid medium to a plurality of spinning cells comprising passing a stream of the fluid through a main supply duct in an amount from two to ten times the volume required by the cells, then passing the stream directly from the supply duct into and through a contiguous return duct, withdrawing the requirements for the cells from the stream at spaced points therealong, and maintaining the stream in the return duct in heat interchange relationship with the stream in the main supply duct through a closed heat-conductive partition constituting a portion of both ducts all along that portion of their length coextensive with said spaced points of withdrawal.

13. A method for supplying a fluid medium to a plurality of spinning cells comprising passing a stream of the fluid through a main supply duct in large excess of the amount required by the cells, then passing the stream directly from the supply duct into and through a contiguous return duct, withdrawing the requirements for the cells from the stream in the return duct at spaced points therealong, and maintaining the stream in the return duct in heat interchange relationship with the stream in the main supply duct through a closed heat-conductive partition constituting a portion of both ducts all along that portion of their length coextensive with said spaced points of withdrawal.

14. A method for supplying a fluid medium to a plurality of spinning cells comprising passing a stream of the fluid through a main supply duct in large excess of the amount required by the cells, then passing the stream directly from the supply duct into and through a contiguous return duct, the main supply duct surrounding the other, withdrawing the requirements for the cells from the stream in the return duct at spaced points along the contiguously related portions of the ducts, and maintaining the stream in the return duct in heat interchange relationship with the stream in the main supply duct through a closed heat-conductive partition constituting a portion of both ducts all along that portion of their length coextensive with said spaced points of withdrawal.

15. A method for supplying a fluid medium to a plurality of spinning cells comprising passing a stream of the fluid through a main supply duct in large excess of the amount required by the cells, then passing the stream through a contiguous return duct, the return duct surrounding the other, withdrawing the requirements for the cells from the stream in the return duct at spaced points along the contiguously related portions of the ducts, and maintaining the stream in the return duct in heat interchange relationship with the stream in the main supply duct through a closed heat-conductive partition constituting a portion of both ducts all along that portion of their length coextensive with said spaced points of withdrawal.

16. A spinning machine comprising a row of spinning cells, a duct extending lengthwise of the row of cells for supplying a fluid medium to the cells, a return duct contiguous with the first duct, at least one of said ducts constituting means for conducting heat between the ducts and providing a heat-conductive partition between the ducts, said partition being closed along the entire length of the ducts except at one end thereby separating the ducts throughout their length except at said one end where intercommunication is provided, conduits connecting the cells to one of the ducts at spaced points therealong and extending through the other duct in heat exchanging relationship with the medium therein, and means for introducing the medium into the end of the supply duct remote from the aforesaid end.

17. A spinning machine comprising a row of spinning cells, a duct extending lengthwise of the row of cells for supplying a fluid medium to the cells, a return duct contiguous with the first duct, at least one of said ducts constituting means for conducting heat between the ducts and providing a heat-conductive partition between the ducts, said partition being closed along the entire length of the ducts except at one end thereby separating the ducts throughout their length except at said one end where intercommunication is provided, conduits connecting the cells to the supply duct at spaced points therealong and extending through the return duct in heat exchanging relationship with the medium therein, and means for introducing the medium into the end of the supply duct remote from the aforesaid end.

18. A system for distributing a gaseous medium to a plurality of spaced units comprising a duct for supplying a fluid medium to the units, a return duct contiguous with the first duct, at least one of said ducts constituting means for conducting heat between the ducts and providing a heat-conductive partition therebetween constituting a portion of both ducts, said partition being closed along the entire length of the ducts except at one end thereby separating the ducts throughout their length except at said one end where intercommunication is provided, conduits connecting the units to one of the ducts at spaced points therealong and extending through the other duct in heat exchanging relationship with the medium therein, means for introducing the medium into the end of the supply duct remote from the aforesaid end, and an exhaust conduit connected to the return duct at a position remote from the aforesaid intercommunicating end.

19. A system for distributing the gaseous medium to a plurality of spaced units comprising a duct for supplying the fluid medium to the units, a return duct contiguous with the first duct, at least one of said ducts constituting means for conducting heat between the ducts and providing a heat-conductive partition therebetween constituting a portion of both ducts, said partition being closed along the entire length of the

ducts except at one end thereby separating the ducts throughout their length except at said one end where intercommunication is provided, conduits connecting the units to the supply duct at spaced points therealong and extending through the return duct in heat exchanging relationship with the medium therein, means for introducing the medium into the end of the supply duct remote from the aforesaid end, and an exhaust conduit connected to the return duct at a position remote from the aforesaid intercommunicating end.

20. A method for supplying a fluid medium to a plurality of spinning cells comprising passing a stream of the fluid to a main supply duct in large excess of the amount required by the cells, then passing the stream directly from the supply duct into and through a contiguous return duct, one of said ducts surrounding the other, withdrawing fluid for the cells from the inner duct at spaced points therealong and leading the fluid thus withdrawn through conduits extending from the inner duct through the wall of the outer duct in heat exchanging relationship with the region enclosed by the outer duct, and maintaining the stream in the return duct in heat interchange relationship with the stream in the main supply duct through a closed heat-conductive partition constituting a portion of both ducts all along that portion of their length coextensive with said spaced points of withdrawal.

21. A method for supplying a fluid medium to a plurality of spinning cells comprising passing a stream of the fluid through a main supply duct in large excess of the amount required by the cells, then passing a stream directly from the supply duct into and through a contiguous return duct surrounding the supply duct, withdrawing fluid from the supply duct at spaced points therealong transversely through the return duct through conduits in heat exchanging relationship with the region enclosed by the return duct, and maintaining the stream in the return duct in heat interchange relationship with the stream in the main supply duct through a closed heat-conductive partition constituting a portion of both ducts all along that portion of their length coextensive with said spaced points of withdrawal.
